UNITED STATES PATENT OFFICE

PIERRE J. CHÉRON, OF STRATFORD, CONNECTICUT, ASSIGNOR TO THE MOTOMETER COMPANY, INC., OF LONG ISLAND CITY, NEW YORK, A CORPORATION OF NEW YORK

DESIGN FOR A COMBINED TRAFFIC-WARNING DEVICE AND SUPPORT THEREFOR

Application filed June 29, 1929. Serial No. 31,872. Term of patent 14 years.

To all whom it may concern:

Be it known that I, PIERRE J. CHÉRON, a citizen of the United States, residing in Stratford, county of Fairfield, and State of Connecticut, have invented a new, original, and ornamental Design for a Combined Traffic-Warning Device and Support Therefor, of which the following is a specification, reference being had to the accompanying drawing, forming a part thereof.

Figure 1 is a front elevation of a combined

traffic warning device and support therefor; and

Figure 2 is a plan view of the same.

A traffic warning device 1 is mounted in and supported by a motor vehicle radiator shell 2 as shown.

I claim:

The ornamental design for a combined traffic warning device and support therefor substantially as shown and described.

PIERRE J. CHÉRON.
